UNITED STATES PATENT OFFICE.

FREEMAN W. HOOD, OF BOSTON, MASSACHUSETTS.

DESIGN FOR A CHARGE-CYLINDER FOR REVOLVERS.

SPECIFICATION forming part of Design No. 13,824, dated March 27, 1883.

Application filed February 26, 1883. Term of patent 7 years.

To all whom it may concern:

Be it known that I, FREEMAN W. HOOD, of Boston, in the county of Suffolk, of the State of Massachusetts, have invented and produced a new and original Design for the Charge-Cylinders of Revolver Fire-Arms; and I do hereby declare the same to be described in the following specification and represented in the accompanying drawings, of which—

10 Figure 1 is top view, and Fig. 2 a front end view, of such a cylinder provided with my design.

The cylinder is shown as provided not only with the usual cartridge-receiving bores, *a*, arranged in it in a circle about its axis, but as having between certain of such bores others, *b*, smaller in diameter and extending through it from end to end.

15 In carrying out the design I make in the periphery of the cylinder, and between each cartridge-receiving bore and that next to it, two flutes or channels, *c c*, each being curved

transversely of it, and extending from the front end of the cylinder nearly to its rear end, and I have between them a fillet, *d*, round- 25 ed or curved transversely on its outer surface, all being as shown, the several pairs and their rounded fillets, arranged, as represented, in the periphery of the cylinder, constituting the ornamental design therefor. 30

I claim—

The design, substantially as set forth, for the peripheral part of the revolver charge-cylinder, the same consisting in the series of pairs of flutes and their fillets, curved and arranged relatively to each other, and disposed in the cylinder and with respect to the charge chamber or bores thereof, essentially as shown and described. 35

FREEMAN WESTON HOOD.
